(57) **CLAIM**

The ornamental design for a packaging container, as shown and described.

DESCRIPTION

FIG. 1 is a front elevational view of a first embodiment of a packaging container showing the new design;
FIG. 2 is a top plan view of the packaging container shown in FIG. 1;

FIG. 3 is a right side elevational view of the packaging container shown in FIG. 1;

FIG. 4 is a left side elevational view of the packaging container shown in FIG. 1;

FIG. 5 is a sectional view taken along 5-5 in FIG. 1;

FIG. 6 is a perspective view of the packaging container shown in FIG. 1;

FIG. 7 is a perspective reference view of the packaging container shown in FIG. 1, shown with a top portion of the packaging container in an alternate position;

FIG. 8 is a front elevational view of a second embodiment, symmetric to the first embodiment, of a packaging container showing the new design;

FIG. 9 is a top plan view of the packaging container shown in FIG. 8;

FIG. 10 is a right side elevational view of the packaging container shown in FIG. 8;

FIG. 11 is a left side elevational view of the packaging container shown in FIG. 8;

FIG. 12 is a sectional view taken along 12-12 in FIG. 8;

FIG. 13 is a perspective view of the packaging container shown in FIG. 8; and,

FIG. 14 is a perspective reference view of the packaging container shown in FIG. 8, shown with a top portion of the packaging container in an alternate position.

The bottom and rear surfaces of the packaging container are flat and unornamented in both of the first and second embodiments.

(Continued)

In the drawings, the evenly-spaced broken lines showing portions of a packaging container depict environment and form no part of the claimed design. The dash-dot-dash lines represent boundaries of the claimed design and form no part thereof.

1 Claim, 10 Drawing Sheets
